UNITED STATES PATENT OFFICE.

JAMES L. MCCOY, OF PITTSBURGH, PENNSYLVANIA, ASSIGNOR TO WESTINGHOUSE ELECTRIC & MANUFACTURING COMPANY, A CORPORATION OF PENNSYLVANIA.

DISCHARGE-GAP DEVICE.

Application filed December 29, 1925. Serial No. 78,113.

My invention relates to discharge gap devices, and it has particular relation to such devices utilized to protect electric circuits and apparatus against surge voltages.

5 One object of my invention is to provide a discharge gap device comprising four gap electrodes so arranged with respect to each other as to constitute six discharge gaps of equal gap distance.

10 Another object of my invention is to provide an evacuated discharge gap device comprising four electrodes so mounted as to constitute the corners of a regular tetrahedron, all the gaps between said electrodes having 15 substantially the same break-down voltage.

In connection with the development of the supervisory control systems for modern power distribution circuits, the need has been felt for lightning arresters that would provide, in a compact form, a plurality of equally spaced discharge gaps, since such supervisory circuits usually comprise a large number of wires to be protected, and it is inconvenient, as well as expensive, to provide 20 such protection by multiplying the number of individual protective units.

According to my invention, I greatly simplify the wiring, as well as the maintenance work in connection with the protective equipment of supervisory control circuits, or similar multi-wire systems, by providing a protective gap discharge device having four electrodes which are so spaced as to provide 25 six equidistant gaps having the same break-down voltage.

My invention will be best understood by reference to the accompanying drawing, wherein

Fig. 1 is an elevational view of a lightning 40 arrester embodying my invention;

Fig. 2 is a view in detail illustrating the arrangement of the electrodes in the lightning arrester of Fig. 1, and

Fig. 3 is a wiring diagram, showing a protective circuit embodying the lightning arrester shown in Fig. 1.

Referring to Fig. 1, a partially evacuated container 1 of glass, for instance, has mounted therein four spherical electrodes 2, 3, 4 and 5 which are so arranged that the centers thereof constitute corners of a regular tetrahedron, as shown in Fig. 2. The electrodes are preferably made of porous conducting material, such as graphite, in order to prevent the occlusion of gasses during discharge,

and are held on the ends of four leading-in conductors 6, 7, 8 and 9 which are welded into two presses 11 and 12 extending from oppositely disposed tubular extensions 13 and 14 of the envelope.

One extension 14 of the envelope is shown provided with an Edison base 15, two leading-in wires 8 and 9 being suitably connected to the conducting terminals of the base. The other pair of leading-in wires 6 and 7, which are held in the press 11 disposed in the other extension 13 of the envelope, are so disposed that the planes of the two pairs of leading-in wires are perpendicular to each other, this arrangement facilitating the assembly 70 and the correct spacing of the four electrodes.

The spacing between the four spherical electrodes is approximately $\frac{1}{2}$ of an inch between each pair. In manufacturing my 75 arrester tube, the electrode leads are first mounted in pairs in their respective presses 11 and 12 and then the presses are welded into the envelope. The tubes are evacuated and filled with a suitable gas, such as argon, at a pressure which may be of the order of 80 from 2 to 8, inches of mercury. The gas pressure is somewhat higher than that corresponding to the minimum break-down voltage of the gaps, thereby insuring that the 85 gaps will break down between the closest points on the spherical electrodes.

If argon is used, having a minimum break-down voltage of about 250, a voltage of 300 may be impressed upon a pair of electrodes 90 which the argon is being slowly admitted to the evacuated tube, and the argon admission may be stopped when a visible discharge occurs. Having once determined the gas pressure, all of the tubes manufactured may 95 be quickly and automatically filled with argon at that pressure, provided that the electrode material and spacing is the same for all of the tubes.

As may be seen from Fig. 2, the surfaces 100 of the four spherical electrodes constitute six equidistant gaps. By connecting three of the electrodes to three line wires 16 of a supervisory control system or other limited-current system which is to be protected, and by connecting the fourth electrode to ground, as shown in Fig. 3, each of the gaps will 105 break down at the same voltage, securing equal protection of each element of the circuit.

My multigap tube is particularly suitable for supervisory control systems and other circuits utilizing voltages not greatly in excess of normal arcing voltages of 30 or 40, 5 and having sufficient series resistance to limit the current to one ampere or less. It is a property of multigap arrester tubes that the entire space within the tube becomes ionized, so that when one gap breaks down, there is 10 a tendency for all of the gaps to break down. When a very severe overvoltage is applied to one of the electrodes of the arrester, as would be the case if a 11,000-volt power line came into contact with a wire of the supervisory control system, the arrester would break down with a glow discharge at 300 volts, and would remain in the condition of a glow discharge as long as the current remained under about one ampere, which 15 would be during a very small part of a cycle. The discharge would almost immediately be converted into an arc having a discharge voltage of about 40.

It is clear that, if a multigap arrester tube 20 were applied to a 110-volt power line, the line voltage would produce arcs between each line electrode and the grounded electrode. In the supervisory control system to which my invention is applied, however, the normal line voltage is incapable of maintaining 25 an arc of one ampere or more, and hence the supply voltage for the supervisory control is not short-circuited by the operation of the excess voltage arrester.

30 The uniform discharge voltage between each of the pairs of electrodes is desirable because all sorts of conditions including high voltage between any one or more of the lines and each other or ground may be obtained 35 in case of trouble on a supervisory control system, and it is desirable for the discharge to take place between the electrodes having the maximum potential difference between them, in order to quickly blow the high voltage fuses (not shown) with which the 40 system is provided.

I claim as my invention:

1. An overvoltage discharge gap device

comprising four gap electrodes having substantially spherical discharge surfaces, the 50 centers of the four discharge surfaces constituting corners of a regular tetrahedron bounded by four equilateral triangles extending between said centers.

2. An over-voltage discharge device comprising a hermetically closed envelope, four spherical discharge members mounted in said envelope to provide six equally spaced discharge gaps between the individual members, terminal members extending from said discharge members through the walls of said envelope, and a gas of reduced pressure in said envelope.

3. An over-voltage discharge device comprising a hermetically closed glass envelope 65 having two presses on opposite sides thereof, two pairs of rigid leading-in conductors welded in said two presses respectively and extending toward each other from opposite sides within said vessel, substantially spherical discharge electrodes mounted at the inner ends of said conductors so that the centers of the spheres constitute the four corners of a regular tetrahedron, and a gas 70 of reduced pressure in said envelope.

4. An over-voltage discharge device comprising a hermetically closed glass envelope having two presses on opposite sides thereof, said presses extending in longitudinal planes substantially at right angles to each other, two pairs of rigid leading-in conductors welded in said two presses respectively and extending toward each other from opposite sides within said vessel, substantially spherical discharge electrodes mounted at the inner ends of said conductors so that the centers of the spheres constitute the four corners of a regular tetrahedron, and a gas 85 in said envelope having sufficient pressure to insure that the discharge will take place 90 between the points having the closest spacings.

In testimony whereof, I have hereunto subscribed my name this 19th day of December, 1925.

JAMES L. McCOY.
